L. E. MULLER

ELECTRODE HOLDER

Filed Oct. 26, 1925

UNITED STATES PATENT OFFICE.

LOUIS E. MULLER, OF LOS ANGELES, CALIFORNIA.

ELECTRODE HOLDER.

Application filed October 26, 1925. Serial No. 64,842.

My present invention is an electrode holder especially designed to assure a proper cooling and the avoidance of all risks to the user of the same in electric welding operations, or the like.

It is an object of this invention to provide a holder, of the general character referred to comprising a conductive organization within an insulating grip member, with means for bringing a current lead wire diagonally into a clamping device near one end of the mentioned grip; and, in preferred embodiments of my invention, the mentioned conductive organization may comprise an apertured central steel strip at one end of which the mentioned clamping device is provided, within an apertured grip, the apertures of said strip and said grip being intended primarily to assure a proper cooling of the same. Said central strip,—which may be formed of a resilient metal such as steel may terminate forwardly in one of a pair of gripping jaws, may be supplemented, to diminish the resistance of the conductive organization comprising the same, by the use of one or more wires, of superior conductivity, extending substantially parallel with said strip, one or more of said wires being preferably welded, at one end, to said strip or to said clamp,—and the opposite ends thereof being preferably carried forward, through a spacing element (which may support not only the mentioned grip but a flange at the inner end thereof); and when a pair of conductive copper wires are provided, in the indicated manner, on opposite sides of a central steel strip, both of said wires may advantageously be welded thereto in the region of said flange, and one of said wires may advantageously be practically continuous with a second resilient jaw element,—such as a jaw element formed of steel wire; and this latter jaw may also be welded to the steel strip constituting said first mentioned jaw element, in the vicinity of said flange.

Other objects of my invention (which may include a rearwardly extending and externally threaded projection integral with the socket element at the inner end of the mentioned steel strip, and means whereby the rotation of a correspondingly threaded and insulated cap is effective to advance a clamping member into said socket, and may include also threaded means for retaining the mentioned insulating flange between a fixed

shoulder or subsidiary flange and the mentioned grip and the mentioned supporting element, and may also include preferred types of resilient jaws for the retaining of short sections of wire or other stock, to be consumed in welding operations) may be best understood from the following description of an illustrative embodiment thereof, taken in connection with the appended claims and the accompanying drawings, in which

Fig. 1 may be regarded as an elevational view of an electrode holder illustrating my invention, this view being shown from the direction indicated by the arrow 1 of Fig. 2.

Fig. 2 is a longitudinal sectional view, taken substantially as indicated by the line 2—2 of Fig. 1.

Fig. 3 is a transverse sectional view, taken substantially as indicated by the line 3—3 of Fig. 2.

Fig. 4 is an end elevational view, taken substantially as indicated by the arrow 4 of Fig. 2.

Referring to the details of that specific embodiment of my invention chosen for purposes of illustration, 11 may be a substantially central strip of resilient metal, such as steel, this strip being shown as provided with ventilating apertures 12 and as terminating forwardly in a channel shaped jaw 13. The strip 11 may constitute the central element of a conductive organization comprising also one or more wires or rods 14, 15, shown as disposed parallel therewith, these last mentioned elements being formed of a more conductive metal, such as copper, and being respectively welded or otherwise united with the strip 11 near their forward ends,—as in the vicinity of an engagement between the strip 11 and a spacing element 16. The latter is shown as externally threaded, to adapt the same to support an insulating grip 17, and optionally also a flange 18, near one end thereof.

The hollow grip 17 is shown as provided with ventilating apertures 19 and as slightly thickened at 20, in a region which is provided with interior threads; and, instead of employing the end 21 of the mentioned grip securely to retain the flange 11 against a subsidiary flange or shoulder 22, shown as integral with the spacing element 16, I may optionally interpose a threaded retaining ring 23. In case this retaining ring is formed of conductive material, I may op-

tionally cover it with an insulating band or extension 24, which may overlap the adjacent end of the grip 20, or may be integral therewith.

5 One of the conductive wires or rods 14, 15 may terminate, as shown at 25, in such manner as to provide, at 26, a region of maximum flexibility in the strip 11—the channel-shaped jaw 13 being substantially 10 rigid; and a narrow companion jaw 27, which instead of being correspondingly concaved, may have an exterior diameter corresponding to the interior diameter of said channel-shaped jaw, as shown, to render it 15 capable of entering partially therein, may be circular in cross sectional outline, and may be formed practically continuous with another of the mentioned wires or rods (as, the wire or rod 15) by welding a steel rod 20 or wire (at 28) both to the end of the copper wire or rod, and also (at 29) to the strip 11; and the resiliency of the jaw 27 may be 25 further enhanced by the provision of any desired curvature therein, as at 30. A limited flexibility in the jaws 13 and 17 is of course favorable to the secure retention of short sections of any metallic stock, such as wires 31, to be consumed in welding operations.

30 At their inner ends, the strip 11 and the wires or rods 14 and 15 may be united to one another or either or both may be united 35 to a socket element 32, adapted to receive a conductive lead wire, such as the bared end 33 of an insulated copper wire, the mentioned socket being diagonally disposed and positioned favorably to the insertion of the wire 33 through one of the mentioned openings (as the opening 19) in the grip 17; 40 and the mentioned socket element may be integral with a tubular extension 34, which is shown as externally threaded at 35 suitably to engagement by interior threads upon a cap 36 (shown as provided with an insulating cover 37), this cap being adapted, 45 whether or not integral therewith, to impart longitudinal movement to a clamping member 38, shown as engaging the wire 33.

50 As to its mode of use, my electrode holder is intended to be employed, in welding or analogous operations, substantially in the manner with which workers in this art are already familiar, essential advantages of the described construction being: the security 55 of the grip provided by the special construction of the jaws 13 and 27; the high conductivity of the described longitudinally extending interior parts (this high conductivity avoiding local heating effects); the 60 cooling effects assured by the mentioned aperturing of the strip 11 and the tubular insulating grip 17, which surrounds a portion thereof (and also by the lateral spacing of the highly conductive wires or rods 14, 15 from the strip 11); the effective insu-

lating of all parts with which the hands of the user may come in contact; the rigid support of the open-ended grip 17 in spaced relationship from the described conductive organization; and (last but not least), my 70 described use of a diagonally disposed socket member to receive the lead wire or wires 13, and my novel means for securely but reliably clamping said lead wire or wires in said socket. 75

The diagonal disposition of the socket member 32, and the consequent angular relationship between my electrode holder and the insulated wire or cable by which current is brought thereto, are favorable not only 80 to the keeping of said conductor out of the way of the work, but also to the avoidance of any deterioration of the contact, or any breakage at the point of connection,—with a consequent local overheating of parts or 85 interruption of the current, and a corresponding loss of time.

90 Although I have herein described a single complete embodiment of my invention, it should be understood that various features thereof might be independently employed, and also that numerous modifications might be made, by those skilled in the art to which this case relates, without the slightest departure 95 from the spirit and scope of my invention, as the same is indicated above and in the following claims.

I claim as my invention:

1. In an electrode holder of the general character described: a longitudinally extending conductive organization; a laterally apertured insulating grip member surrounding a portion thereof; and means, near one end of said grip member, for supporting the same in spaced relationship to said conductive organization,—said conductive organization comprising a central element formed of a resilient metal and provided, within said grip, with ventilating apertures, and disposed substantially parallel with wires, of a more conductive metal, whose ends are secured thereto. 100 105 110

2. In an electrode holder of the general character described: a longitudinally extending conductive organization; a laterally apertured insulating grip member surrounding a portion thereof; and means, near one end of said grip member, for supporting the same in spaced relationship to said conductive organization,—said organization comprising a narrow jaw and a central strip terminating in a channel-shaped jaw which is resiliently connected and which has an internal diameter corresponding to the external diameter of said narrow jaw. 115 120 125

3. In an electrode holder of the general character described: a longitudinally extending conductive organization; a laterally apertured insulating grip member surrounding a portion thereof; and means, near one 130

end of said grip member, for supporting the same in spaced relationship to said conductive organization,—said conductive organization comprising a steel strip secured within 5 in a threaded spacing element and supplemented by a plurality of copper wires extending through said spacing element.

4. An electrode holder of the general character described: a longitudinally extending 10 conductive organization; a laterally apertured insulating grip member surrounding a portion thereof; and means, near one end of said grip member, for supporting the same in spaced relationship to said conductive 15 organization,—said conductive organization comprising a steel strip secured within a threaded spacing element and supplemented by a plurality of copper wires extending through said spacing element, one 20 of said wires being structurally continuous with a resilient jaw.

5. In an electrode holder of the general character described: a longitudinally extending conductive organization; a laterally 25 apertured insulating grip member surrounding a portion thereof; and means, near one end of said grip member, for supporting the same in spaced relationship to said conductive organization,—said supporting member 30 comprising a threaded body surrounded by an insulating flange, and by one end of said insulating grip.

6. In an electrode holder of the general character described: a longitudinally extending conductive organization; a laterally 35 apertured insulating grip member surrounding a portion thereof; and means, near one end of said grip member, for supporting the same in spaced relationship to said conductive organization,—said conductive organization comprising a lead-receiving socket 40 which is inclined relatively to the longitudinal axis of conductors extending through said grip.

45 7. In an electrode holder of the general character described: a longitudinally extending conductive organization; a laterally

apertured insulating grip member surrounding a portion thereof; and means, near one end of said grip member, for supporting the 50 same in spaced relationship to said conductive organization,—said conductive organization comprising a lead-receiving socket which is inclined relatively to the longitudinal axis of conductors extending through 55 said grip and so disposed as to permit the insertion of a lead wire through a lateral aperture therein.

8. In an electrode holder of the general character described: a longitudinally extending 60 conductive organization; a laterally apertured insulating grip member surrounding a portion thereof; and means, near one end of said grip member, for supporting the same in spaced relationship to said conductive organization,—said conductive organization comprising a lead-receiving socket 65 which is inclined relatively to the longitudinal axis of conductors extending through said grip and is provided with clamping 70 means projecting rearwardly through said grip.

9. In an electrode holder of the general character described: a longitudinally extending conductive organization; a laterally 75 apertured insulating grip member surrounding a portion thereof; and means, near one end of said grip member, for supporting the same in spaced relationship to said conductive organization,—said conductive organization comprising a lead-receiving socket 80 which is inclined relatively to the longitudinal axis of conductors extending through said grip and is provided with clamping means projecting rearwardly through said 85 grip,—said clamping means comprising an externally threaded extension through which projects a lead-engaging member which is movable by the rotation of a cap upon said extension. 90

In testimony whereof, I have hereunto set my hand at Los Angeles, California, this 20th day of October, 1925.

LOUIS E. MULLER.
